UNITED STATES PATENT OFFICE.

ISIDOR ELFENBEIN, OF NEW YORK, N. Y., ASSIGNOR TO UNIQUE HEAD EASER
INCORPORATED, OF NEW YORK, N. Y.

HEAD-EASER.

Specification of Letters Patent. Patented Mar. 23, 1915.

1,133,114.

Application filed November 29, 1913, Serial No. 803,733. Renewed February 9, 1915. Serial No. 7,116.

To all whom it may concern:

Be it known that I, ISIDOR ELFENBEIN, a citizen of the United States, residing at New York, in the county and State of New York, have invented certain new and useful 5 Improvements in Head-Easers, of which the following is a full, clear, and exact specification.

This invention relates to head easers or supports, and has for its object to provide an improved rest for the head designed to be used on a bath tub or a chair for supporting the head in a comfortable position, preventing headaches by removing the 15 strain on the muscles, and protecting the hair from getting wet when taking a bath.

Other objects will become apparent as the description proceeds.

The invention will be first hereinafter described in connection with the accompanying drawings, which constitute a part of this specification, and then more specifically pointed out in the claim at the end of the description.

25 In the accompanying drawings, wherein similar reference characters are used throughout the several views to designate corresponding parts:—Figure 1 is a broken perspective view showing my improved 30 head rest applied to a bath tub, Fig. 2 is a perspective view showing the device applied to a rocking chair, and Fig. 3 is a cross section of the head rest.

The head easer or support consists of a 35 generally rectangular wire frame over which a piece of flexible material, such as cloth, is stretched, said frame giving to the rest proper or cloth a certain resiliency or yielding quality which relieves the strain on 40 the muscles of the back, neck and head, and thus prevents headaches which result from resting the head against the hard surface of a bath tub or chair. The open structure of the device, moreover, renders it entirely 45 sanitary.

As illustrated, the head easer may be made of a frame A of stiff wire having the proper resiliency or yielding quantity, and a rest or support proper of waterproof cloth B riveted 50 or otherwise secured to the front portion of the frame. Said frame may consist of a piece of the wire bent into the form of a rectangle and then bent near the middle to form spaced front and rear portions. 55 The front portion of the frame, which car-

ries the cloth support B, includes one end a of the original rectangle and parts a' of its sides. It is around these parts of the frame that the cloth is folded and secured by rivets C. The rear portion of the frame is disposed substantially parallel to the front portion thereof and includes the other end a^2 of the original rectangle and parts a^3 of its sides, leaving intermediate parts a^4 of said sides arranged preferably at right angles to both front and rear portions of the frame and connecting the same. The rear portion of the frame also has a lower cross piece or brace of the same kind of wire arranged preferably at the junction of the 70 parts a^3 and a^4 .

The end a^2 and brace D, just referred to, are both curved to conform to the curvature of the end of a bath tub or of the back of a chair. To the end a^2 there are independently pivoted two pairs of hooks or attaching members, a pair of large hooks E for attaching the device to a bath tub, and a pair of smaller hooks F for securing the device to the back of a chair. The hooks of 80 both pairs are covered with rubber tubing, as shown at e and f, respectively. By having the hooks separately pivoted, one pair will hang down out of the way when the other pair is in use.

The front cloth covered portion of the frame projects well above the rear portion thereof so as to constitute an extension of the bath tub or chair back when the device is in use. This is an important feature of 90 my invention, for the reason that as a rule the ends of bath tubs and the backs of chairs are shorter than necessary to support the head of an adult person sitting erect. It will also be observed that the upper part 95 of the front portion of the frame is free from the rear portion of said frame, whereby the front portion may yield to the weight or pressure of the head when in engagement with the cloth support, bringing the resiliency of the parts a' and a^4 into play. Said parts a' being relatively long with respect to the rear portion of the frame, increases this resilient or yielding action.

Another important feature of the invention is the leaving of the lower edge of the cloth support free from any cross braces which would be almost sure to come into contact with the head or neck of the user and thus defeat to a great extent the object 110

of the device. Moreover, by leaving the lower edge of the cloth support free, the parts a' and a^4 may yield slightly toward each other, thus increasing the resiliency and comfort of the device.

Having thus described my invention, what I claim as new and desire to secure by Letters Patent of the United States is:—

- 10 A device of the character described comprising a frame made of a single piece of bent wire having a rear portion formed of a transversely extending portion of the wire and two portions of the wire bent at right angles to said transverse portion, said frame
15 also having a front portion formed of a transversely extending portion of the wire and two portions of said wire bent at right angles to said transverse portion of the front part of the frame, said front and rear
20 portions of the frame being connected together by portions of the wire joining the

ends of the right angularly arranged portions of the wire of the front and rear parts at the points farthest removed from their transverse portions, said joining portions 25 of the wire being disposed angularly with respect to the planes of the front and rear portions of the frame, whereby the latter are arranged substantially parallel and spaced one in front of the other, means for 30 attaching the frame to an article of furniture, and a flexible covering for the front portion of the frame to receive the head of the user.

In testimony whereof I have signed my 35 name to this specification in the presence of two attesting witnesses.

ISIDOR ELFENBEIN.
